(57) **CLAIM**

The ornamental design for a curtain rod, as shown and described.

DESCRIPTION

FIG. 1 is a front perspective view of a curtain rod, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged plan view of its top surface;

FIG. 8 is an enlarged plan view of its bottom surface;

FIG. 9 is a perspective view of its storage state;

FIG. 10 is an enlarged detail view of area 10 in FIG. 1;

FIG. 11 is an enlarged detail view of area 11 in FIG. 1;

FIG. 12 is an enlarged detail view of area 12 in FIG. 1;

FIG. 13 is an enlarged detail view of area 13 in FIG. 5; and,

FIG. 14 is an enlarged detail view of area 14 in FIG. 9.

The broken lines in the drawings illustrate the portions of the curtain rod, which form no part of the claimed design.

The dash-dot-dash broken lines encircling the enlarged views are for annotative purposes only and form no part of the claim thereof.

1 Claim, 14 Drawing Sheets
